UNITED STATES PATENT OFFICE.

CHARLES W. HUBBARD, OF WESTON, MASSACHUSETTS.

WINDING AND TWISTING APPARATUS.

1,232,686.

Specification of Letters Patent. Patented July 10, 1917.

Application filed February 7, 1916, Serial No. 76,832. Renewed December 5, 1916. Serial No. 135,273.

To all whom it may concern:

Be it known that I, CHARLES W. HUBBARD, a citizen of the United States, residing at Weston, county of Middlesex, State of Massachusetts, have invented an Improvement in Winding and Twisting Apparatus, of which the following description, in connection with the accompanying drawing, is a specification, like characters on the drawing representing like parts.

This invention relates to an apparatus for winding and twisting yarn and is in the nature of an improvement on the apparatus shown and described in my co-pending application Se. No. 25,386, filed May 3, 1915, some of the purposes of the improvement being to simplify the construction shown in said application and to provide a device which is thoroughly balanced and capable of high speed operation without jar or vibration.

In order to give an understanding of my invention I have illustrated in the drawings a selected embodiment thereof which will now be described, after which the novel features will be pointed out in the appended claims.

Figure 1 of the drawings is a vertical sectional view of a device embodying my invention;

Fig. 2 is a view taken at right angles to Fig. 1 with a portion of the casing broken out to better show the construction;

Fig. 3 is a section on the line 3—3; Fig. 2.

Fig. 4 is a section on the line 4—4, Fig. 2.

The device herein illustrated is similar to that shown and described in my said co-pending application Se. No. 25,386 in that it comprises a yarn receiver in the form of a receptacle 1 in which the yarn mass 2 is built up in transverse layers by means of a winding head including a winding plate 3 that rests on the yarn mass and has a slot 4 therethrough which the yarn 5 is delivered, means being provided for rotating the yarn container 1 and winding plate 3 at different speeds to effect the winding operation. The winding plate 3 is shown as secured to a head 6 by means of posts or pillars 7, said head being rigidly secured to a shaft 8 and driven by means of a suitable gear 9, the shaft being hollow so as to permit the yarn 5 to be led therethrough. The yarn is given a traversing movement as it is laid by means of a vibrating yarn guide 10, as provided for in said application. The yarn container 1 is

provided with a false bottom 11 on which the yarn mass is built up and which is capable of being forced downwardly in the container as the yarn mass accumulates, all as described in said application.

The yarn container is journaled at its lower end in a suitable bearing 12 and at its upper end is detachably secured to a holder 13 having a general bell shape and which is rigidly secured to a sleeve or hollow shaft 14 that encircles the shaft 8 and is driven by a gear 15. The gears 9 and 15 may be driven by any suitable means and at different speeds so as to secure the desired relative movement between the yarn container 1 and the winding plate 3, all as provided in said application.

Associated with the yarn guide 10 is a vibrating compensating member 16 having an eye through which the yarn 5 extends before it is delivered to the yarn guide 10, the object of the compensating member being to cause the yarn to be drawn through the spindle or shaft 8 at a uniform speed, regardless of whether the yarn guide is delivering yarn near the center or near the circumference of the thread mass. It will be understood, of course, that when the yarn guide is delivering yarn at the circumference of the yarn mass, said yarn will be laid more rapidly than when the yarn guide is delivering the yarn near the center of the yarn mass, it being assumed that the yarn mass and winding plate have a fixed relative speed. The compensating member 16 co-acts with the yarn guide 10 to draw surplus yarn through the spindle when the yarn guide is swinging toward the center, and is thus delivering yarn at a decreasing speed, and to give up said surplus yarn when the yarn guide is moving toward the circumference and is thus delivering yarn at a progressively-increasing speed, the result being a uniform delivery of yarn through the spindle 8.

The yarn guide 10 is in the form of an arm secured to a rock-shaft 17 journaled in a bearing 18 formed on the head 6. This rock-shaft 17 is given its oscillatory movement by means of a cam 19 which is rotatably mounted on a stud 20 rising from the head 6, said rock-shaft having an arm 21 provided with a roll which operates in the groove of said cam 19. The compensating member 16 is similarly operated, that is, it is secured to and depends from a rock-shaft 22 journaled

in a bearing 23 formed on the head 6 and having an arm 24 which operates in a cam groove in a cam member 25 that is rotatably mounted on a stud 26 rising from the head 6. These cams 19 and 25 are rotated partly from the shaft 8 and partly from the sleeve 14. Said cams have integral therewith gears 28 and 29, respectively, which mesh with and are driven by a gear 27 that is loosely mounted upon the shaft 8. The gear 27 is driven from the sleeve 14 and this may be accomplished either by making said gear rigid with the shaft or by connecting the gear thereto. In the illustrated embodiment of my invention the gear 27 is provided with clutch teeth 30 which engage corresponding teeth 31 formed on the lower end of the sleeve 14 so that said sleeve and gear will rotate in unison. Since the sleeve 14 and shaft 8 are rotating at different speeds, the result will be a differential motion which will be transmitted to the cams 19 and 26, thereby giving the yarn guide and compensating member their desired vibratory movements. This construction is not only simple and one which embodies few parts, but it also has the advantage that the cams and compensating member and yarn guide are so disposed as to make a perfectly balanced structure, the cams being situated directly opposite each other and the yarn guide and compensating arm being also situated directly opposite each other. As a result the winding head is in perfect balance and can be run at a high speed without developing any particular vibration. The bearing for each of the rock-shafts 17 and 22 is provided with an opening 40 through which the stem of the yarn guide or compensating member extends, the wall 41 of said opening being so disposed that the stem of the yarn guide or compensating member will have bearing thereagainst. These rock shafts are also preferably of such a length that the inner ends 32 thereof bear against the end wall 33 of the bearing when the rock shaft is properly positioned. This construction has the advantage that it facilitates the assembling of the parts and also that the stem of the yarn guide or compensating member acts as a means to retain the corresponding rock shaft in place.

In assembling the parts each rock shaft is inserted into its bearing from the open end thereof until the end of the rock shaft engages the end wall 33, at which time the rock shaft is properly positioned so that the stem of the compensating member or yarn guide can be inserted into the aperture formed in the rock shaft for the reception thereof. The engagement of the stem of the yarn guide or compensating member with the wall 41 holds the rock shaft in position.

34 designates a casing or cover which is screw-threaded to the head 6 and which in-

closes the cams and operating gears. This cover is provided with a hub portion 35 which loosely fits the sleeve 14. It is my intention to lubricate the parts by supplying the interior of the casing 34 with oil, and the construction is such that this casing with the head forms an oil chamber which securely holds the oil and prevents it from escaping. The position of the rock shafts 17 and 22 is such that the centrifugal force will tend to throw the oil toward the outer end of the shaft and thus while these shafts will be sufficiently lubricated, it will not be possible for any oil to work its way along the shaft toward the inner end thereof in sufficient quantities to drop down through the opening 40.

The yarn container 1 is constructed to extend some distance above the winding plate 3 and it may be detachably secured at its upper edge to the housing or holder member 13 in any suitable way. I have herein shown the upper end portion 45 of the container 1 as made somewhat thicker than the body of the container and as connected to the lower end of the member 13 by a bayonet joint lock or an ordinary breech lock, as shown at 46. This thickened upper portion of the yarn container is provided with apertures 36 situated just above the winding plate and through which any lint that accumulates may escape. When the yarn container has been filled and is removed from the holder 13, the yarn mass tends to expand upwardly when the pressure of the winding plate is removed. By having the yarn container extend some little distance above the point where the winding occurs as herein shown, there is plenty of room allowed for this expansion of the yarn without any danger that the top of the yarn mass will be forced out of the yarn container entirely and thus become disarranged. It will be seen that the mechanism herein illustrated is extremely simple and is perfectly balanced thereby making it especially adapted for high speed operation. Moreover, all of the operative parts are entirely inclosed.

The yarn mass is built up in the yarn container on a yarn support herein shown as a plate 51 resting on an expandible plug 52. The expandible plug 52 is made in two sections which are expanded outwardly against the walls of the yarn container by means of spring 54. The friction of the expandible plug against the walls of the yarn container affords sufficient resistance to the downward movement of the yarn mass to cause the yarn to be compactly laid.

The plate 51 is shown as provided with a central depending portion which is received between the two sections of the expandible plug and which supports the spring 54.

While I have illustrated a selected embodiment of my invention, I do not wish to

be limited to the constructional features shown.

I claim:

1. In a twisting and winding apparatus, 5 the combination with a shaft and means for rotating it, of a winding head sustained by the shaft and provided with a slotted winding plate, a vibrating yarn guide mounted on said head, a cam for vibrating said yarn guide rotatably mounted on said head non-axially thereof, said cam having a gear rigid therewith, a gear loosely mounted on said shaft, and means for rotating said gear relative to the shaft thereby to operate said cam.
2. In a device of the class described, the combination with a shaft and means for rotating it, of a winding head sustained thereby and provided with a slotted winding plate, a vibrating yarn guide and a vibrating 15 compensating member both mounted on said head, two cams rotatably mounted on said head and both situated thereon non-axially thereof, one cam operating the yarn guide and the other cam operating the compensating member, each cam having a gear rigid therewith, a gear loosely mounted on said shaft and meshing with both of said cams, and means for rotating said gear relative to the shaft thereby to operate both cams.
3. In a device of the class described, the combination with a vertical shaft, of a winding head sustained thereby and provided with a slotted winding plate, a horizontally-disposed rock shaft mounted on the winding head, a yarn guide secured to said rock shaft, a cam mounted on said head non-axially thereof and operatively connected to the rock shaft, a sleeve encircling said vertical shaft, a yarn container sustained by said sleeve, gearing 20 between said sleeve and said cam, and means for rotating said sleeve and shaft relative to each other.
4. In a device of the class described, the combination with a vertical shaft, of a winding head secured thereto and provided with a slotted winding plate, two horizontally- 25 disposed rock shafts carried by said head, a yarn guide secured to one rock shaft, a compensating member secured to the other rock shaft, two cams carried by said winding head and each situated non-axially thereof, one cam being operatively connected to one rock shaft and the other being operatively connected to the other rock shaft, a gear loosely mounted on said vertical shaft, operative 30 connections between said gear and each cam, and means to rotate said gear relative to the shaft.
5. In a device of the class described, the combination with a vertically-disposed shaft, of a winding head secured thereto and provided with a winding plate, a sleeve encircling said shaft, a yarn container operatively connected with said sleeve, two horizontally-disposed rock shafts carried by said winding head, a yarn guide secured to one of said rock shafts, a compensating member secured to the other rock shaft, a cam for operating each rock shaft, said cams being situated non-axially of the winding head, a gear secured to said sleeve and by which the cams are operated, and means for rotating the sleeve and shaft relative to each other.
6. In a device of the class described, the combination with a rotatable sleeve, of a holder secured to said sleeve, a yarn container detachably secured to said holder, a shaft extending through the sleeve, a winding head secured to said shaft and provided with a winding plate operating in the yarn container and adapted to rest on the yarn mass therein, means for rotating the winding head and the yarn container at different relative speeds, said yarn container extending above the winding plate and having openings therein also above the winding plate.

In testimony whereof, I have signed my name to this specification.

CHARLES W. HUBBARD.
